UNITED STATES PATENT OFFICE.

SAMUEL M. KATHCART, OF POTOSI, MISSOURI, ASSIGNOR OF ONE-HALF TO JAMES M. COOPER, OF POTOSI, MISSOURI.

PIPE WRENCH.

Application filed December 4, 1926. Serial No. 152,618.

The present invention is directed to improvements in wrenches more particularly designed for use in connection with pipes and rods.

5 The primary object of the invention is to provide a wrench of this character including a sliding and a pivoted jaw, the latter being adjustable through the medium of a lever capable of being held in a position to prevent interference and injury to the hands of the user when the wrench is in use, but at the same time permitting its associated jaw to be quickly adjusted for use.

Another object of the invention is to provide a wrench of this character which is simple in construction, the parts thereof being assembled in such relation as to produce a wrench of great strength and durability.

In the accompanying drawing:

20 Figure 1 is a side elevation of the wrench. Figure 2 is a view partly in elevation and partly in vertical section. Figure 3 is a fragmentary back edge view. Figure 4 is a sectional view on line 4—4

25 of Figure 1. Referring to the drawing, the numeral 1 designates the handle having upon one of its edges a housing 2 and guide 3 disposed in spaced relation and in alignment with each other.

Slidable in the housing 2 is the shank 4 of the inner jaw 5, said jaw having its outer face provided with serrations 6, as is customary in wrenches of this type. The shank 4 has formed integral therewith an offset threaded stem 7, the rear end of which is engaged in the guide 3. Threaded upon this stem is a nut 8, which occupies the space between the housing 2 and guide 3 when in its assembled relationship. It is through the instrumentality of this nut that the jaw 5 is adjusted.

40 The upper edge of the forward end of the handle 1 is machined to provide relatively deep and shallow grooves 9 and 10, respectively, and resultant side walls 11 which terminate at their forward ends in spaced ears 12, said ears serving to support a transversely disposed bolt or pin 13, the purpose of

which will later appear. The outer or pivoted jaw 14 is provided upon its inner face with serrations 15 which are oppositely inclined with respect to the serrations 6 of the jaw 5.

55 The shank 16 of the jaw 14 is formed with a relatively narrow web 16' adapted to fit snugly between the ears 12, said web having a perforation 17 therein and in which the bolt 13 is engaged to pivotally sustain the jaw 14 upon the handle 1.

60 The web 16' is provided with an integrally connected rearwardly extending lever 18 capable of occupying the grooves 9 and 10 when the respective jaws are operatively engaged with a pipe or rod.

65 Mounted in the groove 9 is a coil spring 19 which engages the under side of the lever 18 and tends to urge the same outwardly, thus swinging the jaw 14 toward the jaw 5 to permit the respective jaws to intermittently engage the work when the handle 1 is oscillated.

70 When the jaws have firmly gripped the work, the lever 18 will be confined in the grooves 9 and 10, with the upper surface thereof in a plane with the handle edge, the base of the groove 10 serving to limit inward swinging movement of said lever.

75 Thus, it will be seen that when the wrench is in use, the lever will be so positioned as to protect the hands from injury if the hand slips. Owing to the fact that the lever is confined in the grooves, it will not only be protected from injuring the hand, but will also be prevented from catching in the workman's clothes.

80 When it is desired to turn a pipe or rod of comparatively small diameter, the nut 8 is rotated to feed the jaw 6 forwardly until the jaws are spaced approximately a distance 85 corresponding to the diameter of the pipe or rod, whereupon the lever 18 is pressed inwardly to permit the work to enter between the jaws, after which the nut is manipulated to obtain a finer adjustment of the jaw 5.

90 Having thus described the invention, what I claim is:

95 A wrench comprising a handle having rela-

tively deep and shallow grooves formed therein, the walls of the grooves having spaced ears carried thereby, an inner jaw slidably mounted on the handle, an outer 5 jaw including a web pivotally mounted between the ears, said web having a lever, a spring mounted in the deeper groove and

engaged with the lever and tending to urge the outer jaw toward the inner jaw, said lever being confined in the groove when the 10 jaws are engaged with the work.

In testimony whereof I affix my signature.

SAMUEL M. KATHCART. [L.S.]
